UNITED STATES PATENT OFFICE.

AUGUST T. NELSON, OF MILWAUKEE, WISCONSIN, ASSIGNOR, BY DIRECT AND MESNE ASSIGNMENTS, OF FORTY-ONE ONE-HUNDREDTHS TO JOHN GRAVES AND FIFTEEN ONE-HUNDREDTHS TO ARTHUR C. KIECKHEFER, BOTH OF MILWAUKEE, WISCONSIN.

MEANS FOR LOWERING BOATS AT SEA.

1,131,411.

Specification of Letters Patent.

Patented Mar. 9, 1915.

Application filed March 16, 1914. Serial No. 824,931.

To all whom it may concern:

Be it known that I, AUGUST T. NELSON, a citizen of the United States, and resident of Milwaukee, in the county of Milwaukee and State of Wisconsin, have invented new and useful Improvements in Means for Lowering Boats at Sea, of which the following is a description, reference being had to the accompanying drawings, which are a part of this specification.

This invention has relation to mechanism for launching life boats from a ship in distress at sea and has for its object to accomplish the purpose without a suspension of the life boat from the ship with the accompanying danger of crushing the boat when the operation is performed in a rough sea by permitting the boat to swing as a pendulum against the hull of the ship and substituting for such suspension a mechanically controlled lowering saddle operating in guideways on the side of the ship and having the boat merely resting thereupon so that as it lowers beneath the surface of the water the boat is floated in its natural, upright position and is not fouled by either the saddle or the ship.

Another object of the invention is to provide such a boat lowering saddle with outer arms automatically locked in position for holding the boat until the saddle is submerged and the boat is self supporting, when such arms are automatically withdrawn from the boat to permit the boat to be pushed away from the ship without being interfered with by the arms of the saddle.

Another object of the invention is to provide tracks on the upper deck of the ship and trucks traveling on such tracks and locked thereto against displacement and carrying the boats for bringing them successively to the boat lowering mechanism.

Another object of the invention is to provide such boat lowering mechanism in which the saddle is capable of being lifted into extension guides which are capable of folding down upon the upper deck for normally storing the saddle on the upper deck.

Another object of the invention is to provide suitable means for operating and controlling the speed of the means for lifting and lowering the saddle.

Another object of the invention is to provide the saddle with auxiliary guides which

will enable the saddle to be lowered beyond the lower ends of the main guides which may thereby be terminated at the wale strip.

With the above and other objects in view the invention consists in the means for lowering boats at sea as herein claimed and all equivalents.

Referring to the accompanying drawings in which like characters of reference indicate the same parts in the different views: Figure 1 is a side elevation of a portion of a ship equipped with the boat lowering means of the present invention and showing the saddle in position for receiving a boat from the davits; Fig. 2 is a plan view thereof with the davits swung to a position for lifting a boat from a truck, which is not shown; Fig. 3 is a side elevation with parts sectioned and showing in full lines the davits in position for lifting the boat from the truck, and in dotted lines the position for lowering the boat into the saddle; Fig. 4 is a similar view on the water line showing in full lines the saddle lowered to the position in which a boat is floated and showing in dotted lines the position of the saddle in its further downward movement to release the boat; Fig. 5 is a sectional side view of the mechanism with the saddle shown in full lines in the position in which it is stored on the upper deck and shown in dotted lines, first, in the position to which it is moved before swinging the guide extensions to their upright position by means of the tackle on the davits, and then in the position assumed by it when the guide extensions are in their upright position; Fig. 6 is a sectional plan view through the guides and the supplemental guides of the saddle; Fig. 7 is a detail view showing the swinging bridge plate for one of the gaps in the tracks for the trucks on the upper deck; Fig. 8 is a detail view of the ratchet detent for locking the saddle at any desired elevation for loading the boat from any deck; and, Fig. 9 is a detail view of the speed governor for controlling the speed of lowering the saddle in case the man at the friction brake should fail to properly apply the friction brake in lowering the boat.

In these drawings 10 indicates the ship which is provided outside of the rails with a pair of vertical guides 11 fixed firmly in place and extending preferably from the up-

per deck to the wale strip. These guides are slotted with inturned guide flanges, as seen in the plan view in Fig. 2, so as to afford a guideway for slides 12 which are T-shaped in cross section. Referring to Fig. 4, it will be seen that the slides 12 are arranged in pairs, that is, there are two slides 12 in each of the guides 11 and at their outer ends they are connected to vertical, tubular supplemental guides 13 which may be in the form of slotted, cylindrical tubes, as shown, and which have cylindrical slides 14 slidably fitting within them. Rigid brackets 15 project from the cylindrical slides through slots of said supplemental guides and have arms 16 pivotally mounted thereon to form a saddle or boat carrier therewith so long as said arms are held in their upright position, shown by full lines in Fig. 1. The pivotal connections for the two arms 16 are formed by a shaft 17 which is journaled in the two brackets 15, the arms 16 being keyed on the shaft 17 so as to move together. Another shaft 18 is journaled at its ends in the brackets 15 and has a lever 19 fixed thereon which has pivotally connected to it at an intermediate point a bent link 20 which also connects with one of the arms 16 so that the turning of the shaft 18 causes the swinging of the arms 16 between the two extreme positions shown by full lines and dotted lines in Fig. 4. The two supplemental guides 13 are connected by cross rods 21 and 22 and normally the arms 16 are held in their upper position by the said lever 19 having its pivotal connection with the bent link 20 passed beyond the line of centers of the shaft 18 and the other end of the link 20 and in such position the lever 19 projects between the cross rods 21 and 22 so as to be engaged thereby in the upper and lower extreme positions of the slide 14 in the supplemental guides 13 respectively. In the upper position this engagement with the cross rod 21 securely locks the arms 16 against an outward and downward movement, while in the lower position the engagement of the lever 19 with the cross rod 22, taking place near the end of the downward movement of the saddle, causes said lever to be swung and to carry the pivotal connection of the link therewith above the line of centers of the shaft 18 and the other end of the link so that the weight of the arms 16, as well as the cam action of the arm 19 against the cross rod 22, forces the arms 16 to open and lower to the position shown in dotted lines. At the beginning of the upward movement of the saddle the arms 16 are restored to their normal position, the beginning of such movement resulting from the turning action of shaft 18 caused by an arm 23 thereon engaging the cross rod 22. This movement of the arms 16 is only a partial movement and they are held in this intermediate position

by the travel of arm 23 on a guide strip 24 of the supplemental guide 13. Before the arm 23 leaves the guide strip 24 the lever 19 comes into engagement with the cross-piece 21 and is caused thereby to further turn the shaft 18 and complete the upward movement of the arms 16, carrying the pivotal connection of link 20 to the locking position shown in full lines in Fig. 4. A spring pressed dog 25 pivotally mounted on the supplemental guide 13 with its hook end adapted to enter through an opening of said guide normally engages the lower end of the cylindrical slides 14, as shown in Fig. 3. Upon reaching the end of the guide 11 the end of the dog 25 engages the wale strip and is swung thereby out of the supplemental guide 13 so as to permit the saddle to continue in its downward movement notwithstanding the arresting of the supplemental guides 13 by their slides 12 reaching the end of the guides 11, this further movement of the saddle being permitted by the travel of the cylindrical slides 14 within the supplemental guides. On the upward movement of the saddle after lowering the boat the cylindrical slides 14 travel in the supplemental guides 13 until reaching the upper ends thereof, which are closed, and then cause the supplemental guides to continue with them up the guides 11.

It is obvious that any desirable means for raising and lowering the saddle may be employed, but it is preferred to attach a pair of ropes or wire cables 26 to right and left worm drums 27 on a hoisting shaft 28 which is journaled in bearings along the edge of the upper deck, said ropes or cables being connected at their ends, preferably by spring connections 29, with a cross rod 30 which connects the lower ends of brackets 15. The hoisting shaft 28 may be turned by a hand gear 31 or by a hoisting engine 32 having a driving connection therewith including a suitably operated clutch 33 and a ratchet 34, shown in detail in Fig. 8, with a weight-actuated detent treadle 35 enables the hoisting shaft to be locked so as to hold the saddle at any position in its travel. A brake lever 36 controls a friction brake in the usual form of a brakeband surrounding a brakedrum on the shaft 28 and enables the speed of descent to be controlled as desired by the officer in charge of the lowering of the boat, and in order that such descent may not be too rapid an automatic speed governor 37 may also be provided at the end of a shaft. As shown in Fig. 9 the preferred form of speed governor for this purpose comprises a spring pressed ratchet clutch member 38 splined on the shaft 28 and engaging a beveled gear wheel 39 which is otherwise loosely mounted on the shaft 28 and which meshes with a beveled pinion 40 on a vertical shaft 41. The vertical shaft 41 is suitably journaled 130

and carries at its upper end a pair of spring retracted ball governor arms 42 which, as they separate under centrifugal action by the turning of shaft 41, cause their angular lower ends to bear downwardly upon a disk 43 loosely mounted on the shaft 41 but keyed thereto and thus cause the compression of various similar disks 44 between yielding friction plates 45 held stationary between the friction disks. Thus, at a predetermined speed of the shaft 28 the ball governor 42 begins to apply friction to increase with an increased speed and thus restrain the turning movement of the shaft and assure the speed of the descent of the saddle remaining within a predetermined safety speed. The ratchet clutch member 38 permits the upward movement of the saddle to take place without restraint.

At their upper ends the guides 11 have extension guides 46 hinged thereto, said extension guides forming a continuation of the guide passageway T-shaped in cross section of the guides 11 when in their upright position, shown in dotted lines in Fig. 5, so that the slides 12 may be drawn upwardly into such extension guides to the position shown by dotted lines in Fig. 5 and thereupon the extension guides with the saddle and its parts contained therein may be lowered upon the upper deck, as shown in Fig. 5, for storing. The hoisting ropes or cables 26 may be then given slack to permit the parts to run inboard, as shown, to avoid the projection of the extension guides 13 beyond the lines of the ship. When it is desired to place the parts in active position the saddle is run out to near the hinged end of the extension guides 46 and the tackle from the davits is attached to eyes 47 in the side thereof and the extension guides 46 are thereby hoisted to their upright position and the saddle is lowered into the main guides 11 and is ready for operation.

It is contemplated that there will be one of these "lowering outfits" at each side of the ship, preferably near the stern thereof, though there may be any number of them if preferred, but in any event it is desirable to provide means for readily moving the boats from their storage positions along the upper deck to positions where they may be lifted by the davits and swung into the saddles. With this end in view the invention contemplates the use of tracks 48 on the upper deck extending along the edge of the upper deck where it is desired to store the life boats, said tracks having outwardly flanged upper edges on which the flanged rollers 49 of suitable boat trucks 50 may travel, there being hooks 51 on the supports for such rollers engaging beneath the flanges of the tracks to prevent the trucks becoming dislodged from the tracks at any time, due to the motion of the ship or to any other cause.

The tracks 48 are arranged to lead the trucks 50, carrying the life boats 52, to a position back of the pair of davits 53 where the boats may be lifted by the tackle 54 and swung outwardly into the saddle, as shown in Fig. 3. In order that the tracks 48 may not interfere with the extension guides 46 said tracks are provided with openings within which the extension guides may lie and hinged bridge pieces 55 serve to continue the track 75 surface across such openings.

In operation the parts which are stored in the position shown in full lines in Fig. 5 are very quickly brought into active position by lifting the extension guides 46 to their upright position, as shown by dotted lines, and then the saddle may be lowered into the main guides 11 and there held by the ratchet 34 while the extension guides are returned to their lower position on the deck and a boat truck with a life boat thereon is run along the tracks into position to have the boat lifted by the davits and swung outwardly thereby into position in the saddle. The saddle may now be lowered to any one of the decks from which it is desired to take passengers, instead of requiring all of the passengers to take the boat from the upper deck, and when the boat is properly loaded it may be gradually lowered to near the water and may be held there until the ship is in the most desirable position, when a further lowering movement may be permitted to lower the boat into the water, the saddle continuing downwardly until the arms 16 are opened to the position shown in dotted lines in Fig. 4, thus freeing the boat automatically without the necessity for disconnecting tackle blocks as heretofore. As soon as the boat is launched it is pushed away from the ship and the saddle is raised to receive another boat which has been brought into position in the meantime and thus the filling and lowering of boats may be quickly accomplished without the danger of boats swinging against the side of the ship and becoming crushed, as with lowering by tackle from davits, and without the danger of one end of the boat being lowered more rapidly than the other and without the danger of a failure to disconnect the tackle blocks at both ends of the boat as soon as the boat is in the water.

With this invention the lowering of the boat is entirely within the control of the officer in charge, as the brake 36 will permit the speed to be varied at will, but should the brake fail or the officer lose control, the automatic speed controller 37 prevents a rapid descent of the boat and assures a movement which will permit the safe launching of the boat. The lifting of the saddle is intended to be accomplished by the hoisting engine 32, but the hand means 31 is provided for

use in case of the failure of the hoisting engine so that efficient operation is assured under all conditions.

The object in providing the supplemental guides is to enable the saddle to continue its downward movement below the wale strip, for with lake steamers where there is considerable rubbing against docks and protecting piles of bridges and the like it is not desirable to continue the main guide 11 below the wale strip, and the supplemental guide thus enables the saddle to carry its own guide means for use below the wale strip to permit the saddle to become completely submerged in launching the boat. In ocean steamers and others where there is not the same danger to the continuation of the guide 11 to or beneath the water line this may be done and the supplemental guide dispensed with.

As will be seen in Fig. 2 the tracks 48 may terminate immediately after crossing the extension guides 46. However, after removing the life boat from the trucks there is no further need for retaining the trucks on the tracks and they may be withdrawn and disposed of in any desired manner.

What I claim as new and desire to secure by Letters Patent is:

1. Means for lowering boats at sea, comprising fixed guides, guides movable in said fixed guides, a boat support slidably mounted on the movable guides movable to a position beneath the water, and means for raising and lowering the boat support and the movable guides.

2. A boat lowering device, comprising fixed guides, guides movable in said fixed guides, a boat support slidably mounted on said movable guides and for releasably securing a boat therein, and means for raising and lowering the boat support and the movable guides.

3. A boat lowering device, comprising fixed guides, guides movable in said fixed guides, a boat holding saddle slidably mounted on said movable guides and comprising brackets having arms pivotally connected therewith, means for automatically swinging the arms when the saddle is lowered beneath the water, and means for raising and lowering the saddle.

4. A boat lowering device, comprising substantially vertical guides, a boat support 55 saddle slidably mounted on the guides and comprising brackets, a shaft journaled in the brackets, arms fixed on the shaft, a lever fulcrumed on one of the brackets, a bent link connecting the lever with one of the arms, the link connection with the lever being adapted to pass beyond the dead center relation with the pivotal connection of the lever and the pivotal connection of the link with the arm, means in the path of the 60 lever for causing it to swing and thereby

move the arms, and means for raising and lowering the saddle.

5. A boat lowering device, comprising approximately vertical guides extending to the wale strip, supplemental guides slidably mounted therein and in their lower position extending to beneath the water level, boat supports slidably mounted in the supplemental guides, and means for raising and lowering the boat supports in the supplemental guides and the supplemental guides in the first mentioned guides. 70 75

6. In a boat lowering device, approximately vertical slotted guides, slides T-shaped in cross section slidably mounted 80 therein, slotted tubular supplemental guides carried by the slides, boat supports having slides fitting within the supplemental guides, and means for raising and lowering the boat supports in the supplemental guides and the supplemental guides in the first mentioned guides. 85

7. In a boat lowering device, approximately vertical slotted guides extending to the wale strip, slides T-shaped in cross section 90 slidably mounted therein, slotted tubular supplemental guides carried by the slides, boat supports having slides fitting within the supplemental guides, spring pressed dogs on the supplemental guides entering 95 openings through the supplemental guides and engaging the slides therein for holding the boat supports in their upper position in the supplemental guides, said dogs being released on engaging the wale strip, and means 100 for raising and lowering the boat supports in the supplemental guides and the supplemental guides in the first mentioned guides.

8. A boat lowering device, comprising approximately vertical guides, a boat support 105 slidably mounted in the guides, means for raising and lowering the boat support, extension guides pivotally mounted at the upper ends of the first mentioned guides and forming a continuation thereof in which the 110 boat support may travel, and means for swinging the extension guides with the boat support thereon.

9. A boat lowering device, comprising approximately vertical guides, a boat support 115 slidably mounted therein, means for raising and lowering the boat support, extension guides pivotally mounted on the upper ends of the first mentioned guides and forming a continuation thereof in which the boat support 120 may be moved, means for swinging the extension guides with the boat support thereon down upon the upper deck, tracks on the upper deck crossing the extension guides in their lowered position and having 125 gaps therein to receive the extension guides, bridge pieces pivotally mounted to the tracks to bridge over said gaps, boat carrying trucks traveling on the tracks and provided with hooks engaging beneath the 130

heads of the tracks and the bridge pieces thereof, and davits for swinging boats from the trucks to the boat support on the first mentioned guides.

5 10. A boat lowering device, comprising fixed guides, guides movable on said fixed guides, a boat support slidably mounted on said movable guides, means for raising and lowering said movable guides and boat sup-
10 port, and means for controlling the opera-
tion of said raising and lowering means.

11. A boat lowering device comprising fixed guides, guides movable in said fixed guides, a boat support slidably mounted on
15 said movable guides, means on said boat support for releasably securing a boat, means for operating said releasable securing means when the support has reached the end of its travel in the movable guides and
20 means for raising and lowering the boat support.

12. A boat lowering device comprising fixed guides, guides movable in said fixed guides, a boat support slidably mounted on
25 said movable guides, means for preventing the sliding movement of the boat support until the movable guides have reached the end of their travel on the fixed guides and means for raising and lowering the boat sup-
30 port.

13. A boat lowering device comprising fixed guides, guides movable in said fixed guides, a boat support slidably mounted on
35 said movable guides comprising brackets with swinging arms thereon, means coöperating with the movable guide for automatically swinging the arms when the boat support is lowered beneath the water and means for raising and lowering the boat support.

40 14. A boat lowering device comprising fixed guides, guides movable in said fixed guides, a boat support slidably mounted on
45 said movable guides, means for preventing the sliding movement of the boat support until the movable guides have reached the end of their travel on the fixed guides, means on said boat support for releasably securing a boat thereon, means for operating said releasable securing means when the sup-
50 port has reached the end of its travel on the

movable guides, and means for raising and lowering the boat support.

15. A boat lowering device, comprising guides, a boat support slidably mounted in said guides, said boat support comprising 55 a bracket and releasable means coöperating with said bracket for securing a boat thereon, means on said guides for automatically operating said releasing means to release the boat and to restore said means to opera-
60 tive position.

16. A boat lowering device comprising guides, a boat support slidably mounted on said guides, said boat support comprising a bracket and arms pivotally secured to the 65 bracket, means operated automatically by the movement of the boat support on the guides to open or close said arms to releasably support a boat on said support and means for raising and lowering the boat 70 support and for controlling the operation of said raising and lowering means.

17. A boat lowering device comprising guides, a boat support slidably mounted on said guides, said boat support comprising a 75 bracket and arms pivotally secured to the bracket, means comprising a plurality of levers one of said levers engaging with means on said guides during the movement of the support on said guides to open or 80 close said arms to releasably support a boat, and means for raising and lowering the boat support.

18. In a boat lowering device, guides, a boat support slidably mounted on said 85 guides, said support comprising a bracket and swinging arms secured thereto, means for operating the swinging arms, means on the guides for operating said arm operating means, and means connected to said arm 90 operating means and operated by the means on the guide for limiting the movement of said arms.

In testimony whereof, I affix my signature, in presence of two witnesses. 95

AUGUST T. NELSON.
